P. S. JONES.
SNAP FASTENER.
FILED SEPT. 12, 1921.

INVENTOR

PAUL S. JONES,
by Ralph Neish ATTORNEY

UNITED STATES PATENT OFFICE.

PAUL S. JONES, OF ST. LOUIS, MISSOURI.

SNAP FASTENER.

Application filed September 12, 1921. Serial No. 499,908.

To all whom it may concern:

Be it known that I, PAUL S. JONES, a citizen of the United States, residing at the city of St. Louis, State of Missouri, have 5 invented a certain new and useful Improvement in Snap Fasteners, of which the following is a specification, reference being had to the accompanying drawing, forming a part thereof.

10 This invention relates generally to snap fasteners and, more particularly, to snap fasteners of the type comprising separable elements for use on wearing apparel.

15 The principal object of my present invention is to provide a fastener of the type stated of simple, durable, and inexpensive construction comprising readily separable elements which, when united, are substantially incapable of relative movement, to the 20 end that the apparel parts to which the elements are attached are relatively immovably fixed.

25 A further object of my invention is to provide a snap fastener element having a "snap" seat formed by rolling or drawing an integral part of the element, thereby forming a relatively inexpensive seat or receiving part for the spring-retainer of the companion element, and which part by its formation is relatively rigid and less liable to distortion than those of the art of which I am aware.

30 A still further object of my invention is to generally improve upon and simplify the construction of snap-fasteners of the kind described.

35 With the above and other objects in view, my present invention resides in the novel features of form, construction, arrangement, 40 and combination of parts hereinafter described and afterwards pointed out in the claim.

In the accompanying drawing,

45 Figure 1 is an inverted plan view of the fastener-element having the spring receiving seat;

Figure 2 is a plan view of the fastener-element having the spring locking-element;

50 Figure 3 is a sectional elevation of the element shown in Figure 1;

Figure 4 is a sectional elevation of the element shown in Figure 2; and

Figure 5 is a sectional elevation of a snap fastener embodying my invention, its

two co-operating and complementing elements or members being shown as united and relatively locked.

Referring now more in detail to the drawing, which illustrates a practical embodiment of my invention, and in which like reference characters refer to like parts throughout the several views, 1 designates the seat or "locked" element of the fastener and 2 the spring or "locking" element, each of which comprises a body formed of a single piece of suitable material and preferably formed as a disk of sheet metal.

By preference, the elements or members 1 and 2 each comprise substantially flat or plane bodies 3 and 4, respectively, surrounded by rims 5 and 6, respectively, which rims, when the members 1 and 2 are juxtaposed, are relatively spaced to form a gap 7, whereby the separation of the elements is facilitated by wedging action of the fingers or the like into the gap.

The seat or locked element 1 comprises a roll or head 8 preferably in the form of an open ended cylinder constructed integrally out of the body of the element as by forming parallel incisions from its margin and rolling or drawing the intermediate material between such incisions, and of which cylinder the bowed or lenticular sides 9 are the essentials and which provide the lock-receiving seats 10, 11, which are relatively divergent upwardly or away from the plane of the body to a point within the height of the roll and then relatively convergent toward the top of the roll.

The element 2 is provided with upstanding flanges 12 preferably struck from the plane body 4, and between which is formed a substantially rectangular opening or aperture 13 shaped to admit the insertion of the roll or head 8 of the element 1 therethrough and preferably of dimensions to snugly fit the roll or head 8 to prevent relative movement of the elements 1 and 2 when detachably united.

The lock proper consists of a substantially U-shaped spring constructed of a single section of wire and whose legs 14 and 15 are disposed along opposite margins of the opening 13 and held relatively spaced by the upstanding flanges 12 and against movement lengthwise by being secured in the rim 6 as by having the rim crimped thereover, as

shown. The lock is preferably made and secured as shown in Figure 2, and its essential is a yieldingly mounted "bar," such as the leg 14, whose normal or locking position is within the plane of the opening 13, whereby said bar or leg will normally, as when in locking position, be against the seat 10 of the roll or head 8 of the element 1, as shown in Figure 5, the locking engagement between the bar 10 and roll or head 8 being supplemented by the yielding tension of the other leg or bar 15 of the spring.

My new snap fastener may be conveniently and inexpensively manufactured, may be readily attached to the wearing-apparel, thread-openings 16 being provided in the elements for the purpose, and is exceedingly efficient in use and operation.

I am aware that changes in the form, construction, arrangement, and combination of the several parts of my new snap fastener may be made and substituted for those herein shown and described without departing from the nature and principle of my invention.

Having thus described my invention, what

I claim and desire to secure by Letters Patent is:

A snap-fastener comprising a member including an approximately flat disk-shaped body-portion provided with an approximately rectangular aperture, a substantially U-shaped spring having engagement at its bight and at one of its ends with said body-portion, the legs of the spring being disposed upon opposite sides and normally approximately in the plane of said aperture, and upstanding flanges disposed on said body-portion upon opposite sides of the aperture and having engagement with the legs of the spring for maintaining the same in spaced relation, in combination with a second complementing member including a similar approximately flat disk-shaped body-portion provided integrally with a cylindrical head shaped up therefrom and adapted for projection through the aperture of the first member and for locking engagement with said spring.

In testimony whereof, I have signed my name to this specification.

PAUL S. JONES.
